The ornamental design for an ice maker appliance, as shown and described.

DESCRIPTION

FIG. 1 is a perspective view of an ice maker appliance showing my new design;

FIG. 2 is a front view thereof;

FIG. 3 is a side view thereof;

FIG. 4 is another side view thereof;

FIG. 5 is a top view thereof;

FIG. 6 is a bottom view thereof; and,

FIG. 7 is a review view thereof.

The broken lines shown in FIGS. 2, 3, 4, 6, and 7 of the drawings show unclaimed subject matter only and form no part of the claimed design. The shade lines in the figures show contour and not surface ornamentation.
